BRUSH

Edmundo Mar, El Paso, Tex., assignor of one-half to Minnie Lockhart, El Paso, Tex.

Application January 29, 1931, Serial No. 512,172.
Renewed October 13, 1933. In Mexico January 30, 1930

5 Claims. (Cl. 15—194)

This invention relates to brushes such as are used in barber shops and beauty parlors and, among other objects, aims to provide an improved handle having provision to secure a bundle of fibers or bristles in the handle socket and improved means whereby the fibers may be quickly removed and replaced so that a new or clean brush may be used on each customer.

Other aims and advantages of the invention will appear in the following description, when considered in connection with the accompanying drawing, wherein:

Fig. 1 is a side elevation of a brush embodying the invention;

Fig. 2 is a central, sectional view of the brush shown in Fig. 1;

Fig. 3 is a sectional view taken on the line 3—3 of Fig. 2; and

Fig. 4 is a fragmentary sectional view showing a slightly modified form of brush.

Ordinary brushes, such as are used in barber shops and beauty parlors, require frequent sterilization to avoid contamination of the fibers or bristles and to prevent the spread of diseases. Some customers refuse to permit the ordinary barber's brush to be used on them but prefer to have individual brushes. It is the principal aim of this invention to provide a greatly improved brush handle having provision to eject the bristles and to permit a new bunch of hair, fiber or bristles to be inserted so that a sanitary brush in the same handle can be used on different customers.

Referring particularly to the drawing, the brush handle is shown as being made in two sections or parts which may be of any suitable material and comprises a brush holding or lower part 10 and a screw carrying or upper part 11 rotatably mounted on the brush holding part or section. Referring to Fig. 2, the brush holding part is shown as having a flared bristle socket or opening 12 in the lower end to receive a bundle of fibers or bristles 13 suitably tied together or bent upon themselves to form a loop 14 at the upper end, as shown in Fig. 2.

The screw carrying part 11 of the handle preferably has a cylindrical projection 15 inserted in an axial, cylindrical opening 16 in the upper end of the part 10 and is secured for relative rotation with respect to said part by means of pins or screws 17 having projections which extend into an annular groove or channel 18.

The upper section 11 is hollow and preferably has multiple screw-threads 19 in the form of helicoidal surfaces generated by angles of equal

sides whose vertices lean upon helical lines of constant pitch. A screw member 20 in the form of a cylindrical block having screw-threads mating with the threads 19 is mounted in the upper part and carries a non-circular or prismatic plunger 60 rod or bar 21 which extends through a non-circular axial opening 22 in the lower part and this plunger carries a suitable hook 23 which may have either a rounded or pointed end to engage the bristles or a loop on a bundle of fibers as the case may be. In Fig. 2 a wire or rubber loop or ring 24 is arranged on the bent portion of the fibers and is connected to the hook 23. The arrangement is such that the upper part 11 of the handle may be turned to eject the bristles or fibers 65 by means of the plunger and to pull a new bundle of fibers into the socket.

In Fig. 2, there is shown brush expelling means in the form of a coil spring 25 within a cylindrical recess 26 around the lower hooked end 70 of the plunger and adapted to be compressed by the bundle of fibers or bristles so that, when the plunger is moved downwardly to eject the fibers, the spring will assist in expelling them from the socket. It is contemplated, however, that the 75 plunger may be retracted or pulled inwardly sufficiently far to break the loop 24 so that the spring will eject the loose bristles. This may be done when the bristles are to be destroyed.

The upper and lower sections of the handle 80 are preferably knurled or roughened, as indicated in Fig. 1, to provide convenient gripping surfaces and enable the user to turn the sections relative to each other. The multiple screw-threads, 85 when such threads are used, enable the bristles 90 to be ejected and replaced by turning the sections only a few turns. The bristles are preferably treated to soften the end portions which rub the face and are impregnated with soap or cosmetics so that they are ready for instant use. 95

For barber shop use, especially when cheap bristles are employed, it is desirable to provide means to destroy the bristles or render them useless after they have been used on one customer. This may be accomplished in various 100 ways. For example, the bill of the hook may be so shaped that, when it is removed from the loop of the brush it will scuff or displace the fibers. However, in Fig. 4 there is shown means to render the bristles useless. In this example, a 105 knife blade 27 is secured in the handle section 10 and projects into the socket 12 below the spring 25. The bundle of bristles 13' is tied below the loop portion 14', in which the plunger hook 23 engages, by a string or band 28. This 110

band is cut by the knife as the bundle of bristles is pulled into the socket. Thus, the fibers are loose and some of them are displaced or tangled when ejected. When using this type of brush, a barber has to insert a new bundle of bristles every time a used bundle is ejected.

It will be seen that the improved brush handle may be used almost indefinitely and plain, soaped or powdered bristles of different types or 10 degrees of fineness to suit the needs of the user may be carried in stock ready to be secured in the handle socket. One set of handles with differently shaped sockets may be provided for different sizes of brushes or kinds of bristles. A 15 new or sterilized set of bristles of the same size may be put in the handle for each customer. It will be understood that many variations of the bundles of fibers or bristles may be used and that the mode of connecting them to the handle, as 20 well as the shape of the socket, may be widely varied.

Obviously, the present invention is not restricted to the particular embodiment thereof herein shown and described.

25 What I claim is:—

1. A brush of the character described, in combination, a handle portion presenting a bristle socket in the lower end; a rotatable portion constituting a part of the handle and removably connected to the bristle carrying portion; screw- 30 threads within said rotatable portion; a screw-threaded plunger member mounted in said screw-threaded portion of the rotatable member and projecting into the socket portion; said plunger member having a non-circular part slidably and 35 non-rotatably mounted in the socket portion; a hook member carried by the plunger member; and a bundle of bristles removably secured to said hook member whereby the plunger is utilized to seat the bristles within said socket and 40 to expel them therefrom so that a new bundle of bristles may be substituted therefor.

2. A brush of the character described comprising a two-part handle, one part being rotatably 45 secured to the other; a bristle socket formed in the lower end of one part; a hollow screw-threaded portion in the other part; a non-circu-

lar plunger member having an enlarged screw-threaded head within said hollow screw-threaded portion; said socket part having a non-circular opening in which the plunger is slidably mounted and hook means on the lower end of the plunger adapted to be removably connected to a bundle of bristles so that the bristles may be removed and new ones substituted therefor.

3. A brush of the character described comprising a bristle carrying handle portion presenting a flared socket at the lower end and having a cylindrical recess in the upper end; an upper handle section having a cylindrical extension mounted in said cylindrical recess in the bristle carrying portion; means connecting said portions together so that one may rotate with respect to the other; multiple screw-threads in the hollow portion of the upper section; a non-circular plunger having a screw-threaded enlargement mounted in the screw-threaded portion of the upper section, said lower section having a non-circular opening to receive said plunger and prevent it from rotating; a hook member on the lower end of the plunger extending into the bristle socket; a bundle of fibers or bristles removably secured to the hook member whereby the fibers or bristles may be seated in the socket or expelled therefrom; and a coil spring in the upper end of the socket arranged to assist in expelling the bristles.

4. A brush comprising a hollow handle having a bristle socket; screw means in the handle having a member adapted to secure a bundle of bristles in the socket; and a spring in the socket to expel the bristles therefrom.

5. In a brush of the class described, a handle having a bristle socket; a bundle of bristles composed of reversely bent fibers or hair; a binding band below the upper bent portion; a screw-operated plunger having a hook to engage the loop in the bundle of bristles and pull it into the socket; and a knife blade in the handle projecting into the socket arranged to cut the binding band as the bundle of bristles is pulled home so as to render the bundle useless after it is removed.
